UNITED STATES PATENT OFFICE.

JOSEPH J. CARR, OF WILKES-BARRÉ, PENNSYLVANIA, ASSIGNOR TO THE
WILKES-BARRÉ MOLDING MACHINE COMPANY, OF SAME PLACE.

MOLD-FORMING DEVICE.

SPECIFICATION forming part of Letters Patent No. 409,666, dated August 27, 1889.

Application filed May 31, 1888. Serial No. 275,644. (No model.)

To all whom it may concern:

Be it known that I, JOSEPH J. CARR, a citizen of the United States, residing in Wilkes-Barré, in the county of Luzerne, in the State 5 of Pennsylvania, have invented certain new and useful Improvements in Mold-Forming Devices, of which the following is a specification.

My invention relates to devices used for 10 forming circular forms or patterns in molding sand contained in a flask, and employed, preparatory to the compression of the sand by a pattern of the ultimate configuration, to so distribute the mass of sand within the 15 flask as to impart to it an approximation of the designed ultimate form into which the final pressing pattern is to afterward compact it.

The object of my invention is the provision 20 of a simple and inexpensive device adapted to perform the function stated with accuracy and speed.

A convenient embodiment of my invention is represented in the drawings and described 25 in this specification, the particular subject matter claimed as novel being hereinafter definitely specified.

In the drawings, Figure 1 is a side elevation 30 of an apparatus embodying my invention. Fig. 2 is a central sectional view of the drag of a flask for car wheels after the sand contained in the same has been operated upon by the shaping device shown in Fig. 1.

Fig. 3 is a perspective view of what I term 35 the "sweeper arm." Fig. 4 is a magnified detail of the same, being a section taken on the dotted line xx of Fig. 3, and sight being taken in the direction of the arrow upon said line. Fig. 5 is a top plan view of the feathered 40 bevel pinion employed to drive the shaft.

Similar letters of reference indicate corresponding parts.

In the drawings, A is a cross beam or supporting timber, and a a bracket bearing 45 mounted upon the same. B is a vertical shaft supported in said bearing, and free for rotary and to a limited extent for vertical, movement with respect thereto. To the lower end of the shaft is rigidly attached what I term 50 a "sweeper arm" C. This arm may be made of any desired form and material, and at-

tached to the shaft B in any desired manner. In the drawings it is shown as attached by means of a metal strap c . The lower edge of the arm is shaped to the radial top outline of 55 the concentric pattern into which the sand is to be swept. To that side of the arm which in the rotation of the device is the front side, is attached a sweeper flange D. This flange, which is preferably made of sheet metal, conforms to the outline of the lower edge of the arm, and is conveniently provided with upturned clips d through which it may be screwed thereto. As shown in the drawings and particularly in Fig. 4, the flange has a 65 slight forward and downward droop, so that its front edge lies below the edge nearest the arm C.

E is a roller, mounted upon an axle e , supported in any convenient manner from the 70 shaft B. I prefer to support it as shown, that is to say, by means of a sleeve F mounted upon the shaft B and rigidly but adjustably held in position thereon by the screw f , and from which sleeve depends a bracket arm f' 75 in which the axle e finds a bearing. The roller E possesses a circumferential contour, the outline of which is the counterpart of that of the lower edge of the arm C, and cooperates as a valuable auxiliary with said 80 arm in reducing the sand of the flask to the form desired.

J is the drag flask and K the sand contained therein.

G is a beveled pinion feathered upon the 85 upper portion of the shaft B in such position as to rest upon the bracket a . A correspondingly beveled spur wheel H, shown in Fig. 1, is suitably mounted for engagement with the pinion G, and being driven in any convenient 90 manner drives the machine. The upper end of the shaft B is equipped with two circumferential rings or collars b of any suitable character.

I is a lever arm, suitably fulcrumed in any 95 desired manner at the point i , and having its inner extremity bifurcated, so that its prongs embrace the shaft between its collars b .

The operation of the device will be understood from the foregoing description; rotation 100 imparted to the spur wheel H occasions the rotation of the pinion G and with it the

shaft B and its connected devices. Through the instrumentality of the arm I the shaft B and its connected sweeper arm and roller may be lowered to act upon sand within a flask 5 placed under the device, and, after the operation has taken place, be raised to permit the removal of the flask,—all of which is accomplished without reference to the rotation of the shaft B, for, as is obvious, the pinion 10 G being held against downward movement by the bracket a and against upward movement when the shaft B is raised, by its own weight and its engagement with the spur wheel H,—is always in position to be acted 15 upon by said wheel.

It will be understood, of course, that while I have shown and herein described my invention as employed in connection with car wheel molds, it is nevertheless of use in connection 20 with molds of many other kinds, the car wheel mold referred to being simply a convenient device in connection with which to describe the invention.

Having thus described my invention, I claim:—

In a device for forming molds for car wheels, in combination, a vertical shaft, a roller and a sweeper arm, which radially and horizontally project from the lower end of said shaft, the lower face of the arm and the 25 outline of the roller corresponding to the configuration of the mold to be produced, a projecting flange attached to one side of the arm and following the curvature of the lower face thereof, and vertically adjustable devices for 30 attaching the roller to the shaft, substantially as set forth.

In testimony that I claim the foregoing as my invention I have hereunto signed my name this 29th day of May, A. D. 1888.

JOSEPH J. CARR.

In presence of—

J. BONSALL TAYLOR,
WM. C. STRAWBRIDGE.
